[57] CLAIM

The ornamental design for a hanging tag for luggage, as shown and described.

DESCRIPTION

FIG. 1 is a perspective view of the present invention of a hanging tag for luggage showing my design;

FIG. 2 is a top plan view thereof;

FIG. 3 is a front elevational view thereof;

FIG. 4 is a bottom plan view thereof;

FIG. 5 is a left side elevational view thereof;

FIG. 6 is a right side elevational view thereof;

FIG. 7 is a rear elevational view thereof;

FIG. 8 is a perspective view showing the hanging tag for luggage of FIG. 1 being stretched out; and,

FIG. 9 is a perspective view showing the hanging tag for luggage of FIG. 1 being swiveled.
